UNITED STATES PATENT OFFICE.

JOHN NEWMANN, OF GLENDALE, NEW YORK.

GAS ENGINE.

Original application filed June 30, 1921, Serial No. 481,499. Divided and this application filed May 12, 1925. Serial No. 29,677. Renewed June 9, 1928.

This invention relates to internal combustion motors and more particularly to improvements in the construction and operation thereof with a view of generally improving the efficiency of this class of engines.

Especially this invention relates to an improved mechanism for driving the exhaust and intake valves and for driving a force feed oil pump, and this application is a division of my former application Serial Number 481,499 filed June 30, 1921.

An object is to produce an internal combustion motor comprising a combination of new features which makes this engine highly adaptable for aeronautical and automotive purposes and particularly an object is to produce novel efficient combination force feed pumping and valve driving means.

Furthermore it is the object to produce an improved engine of the radial cylinder type having a plurality of cylinders grouped about a common crank case, and having a crank shaft with a single crank-throw common to all the piston connecting rods. In this invention, I also have in view certain objects such as to make an improved cylinder head valve construction which lends itself to air cooling. Likewise it is an object to produce an engine having an improved valve and head structure of such design as will allow of a rapid discharge the exhaust gases and in-flow of the intake gases.

The accompanying drawings show the principle and an embodiment of my invention, and though I have illustrated and described a preferred form of engine construction and operation, I claim a right of protection as to all such changes as obviously come within the scope of my invention.

Figure 1 shows my engine assembly in sectional view to illustrate my invention in the valve drive and pump combination.

Figure 2 shows a sectional fragmentary view taken on the line 2—2 of Figure 1 to show an eccentric drive for the valve and pump combination.

Figure 3 is a sectional view taken on the line 3—3 of Figure 1 to show the valve ports.

Referring now more particularly to the drawings for a detailed description of the invention, there is shown a plurality of

cylinders 10 radially mounted on a crank case 11. A piston 12 is confined in each cylinder and is attached to a connecting rod 13 which is journaled on the crank 22 of the engine crank shaft 20 and the crank carries counterweights 24 and 25.

A valve plate seat 34 is anchored in the top of each cylinder head, and has a plurality of radially arranged intake ports 35 and exhaust ports 36 made therein. The ports 35 and 36 are periodically opened and closed to properly time the flow of fuel gas into the cylinder 10 and discharge the exhaust and burnt gas therefrom. The inner face of the valve seat 34 is preferably made plane or flat, and a disc valve 73 rotates in close contact with the inner plane face of the valve plate to regulate the opening and closing of the aforesaid intake and exhaust ports.

A cover sleeve, comprising a cylindrical wall 42 integrally formed with a head 43, is disposed over the valve seat 34. The head 43 of this cover sleeve is provided with a number of radial ribs 44 employed to radiate the heat and facilitate the cooling of the cylinder head.

The disc valve 73 is rotated against the inner face of the valve seat 34 to open and close the intake and exhaust ports 35 and 36. The valve 73 is anchored to a valve shaft 74 mounted in a bushing set in the valve head parts. A gear 75 is fixed to the upper end of the valve shaft 74 and driven, as later described. The valve 73 is made with radial slits or openings 76 which periodically pass over the intake ports 35 and exhaust ports 36 of the valve seat 34 to open and close said ports. The openings 76 made in the valve 73 correspond in number to the number of intake ports 35, and likewise correspond in number to the number of discharge ports 76 so that all the intake ports or exhaust ports are quickly opened to provide a very large intake passage or discharge passage to and from the cylinder. A cover 77 is perforated to admit air and fits over the cylinder head to enclose the gear and cylinder head.

An eccentric 79 is fixed on the crank shaft; and a gear 80 in the form of an eccentric strap is confined on the eccentric with bearings disposed therebetween. The gear 80 is provided with improved oval or rounded teeth made on the periphery thereof. An

other gear 82 with internal teeth conforming to the contour of the teeth of the eccentrically driven gear 80 and meshing therewith, is journalled on a hub 83 made on the 5 side wall of the crank case. The gear 82 is made with bevelled gear teeth on the periphery thereof which engages a drive pinion 84 which is journalled in a bearing carried on the side wall of the crank case. A drive 10 shaft 85 is fixed to the drive pinion 84 and has a drive pinion 86 made on the upper end thereof to engage the gear 75 to revolve the valve 73 inside the cylinder. The drive shaft 85 is provided with a universal joint 15 87 to accommodate the angular operation of the shaft 85.

A pump housing 90 is carried on the engine above the eccentrically driven gear 80 and supports a journal stud pin 91. The 20 journal 91 is made with oil passages 92 and oil pipes 93 connect with the passages for the purpose of admitting oil through the journal pin 91 to a pump as well as for conveying the oil therefrom under pressure to 25 be distributed to various parts of the engine through pipes not shown. A pump cylinder 94 is suspended on the journal pin 91 and is fitted with a piston 95. A piston rod 81 is anchored to the piston 95 and is preferably integral with the eccentric strap gear 80 to reciprocate the piston in the cylinder 94 under the action of the eccentric 79.

In the operation of the engine, the crank shaft rotates under the power impulses of 35 the plurality of pistons which produce the motive force delivered from the crank shaft of the radial motor. The crank shaft is shown broken away on the front side of the engine, but it is understood that it is extended to receive the propeller hub of an 40 air screw or clutch member of an automobile, such parts not being shown.

The valve 73 is rotated by the gear 82, and as previously pointed out, the gear 82 is 45 driven by the intermittent contact of the eccentrically driven gear 80. As the eccentric rotates the gear 80 which is held against rotation by the piston rod 81 follows an orbital path around the crank shaft. The teeth 50 on the periphery of the gear 80 are thereby brought into intermittent contact with the internal teeth of the gear 82, and by this action the large bevel gear 82 is driven to operate the valve 73.

55 Blank tooth spaces 100 are preferably made on the lower and upper part of the periphery of the gear 80 because these teeth are not in fact required due to the action of the eccentric thereby causing the blank 60 space 100 of the gear 80 to slip across the gear 82 and thus cause a continuous motion of the gear 82. When the eccentric reaches its lowest or uppermost point of travel the blank toothless spaces do not interfere with 65 continuous rotary motion because the two

gears are always in mesh. The teeth on one side of the blank spaces 100 always mesh before the teeth on the other side move out of mesh. Rotation of the eccentric 79 imparts a quick accelerated and retarded motion to the valves, which is similar to the movement of the pistons in the cylinders to afford maximum power for a minimum of fuel, as well as makes for the smooth, uniform and flexible operation so desirable in 75 an internal combustion motor. As the eccentric goes down its teeth act to carry with it the teeth of gear 82 thus rotating it, and in the same way as the eccentric goes up its action is to continue the rotation of gear 82. 80

It will be observed that the gear 82 performs the double function of driving the force feed oil pump 94 and the valve 73 as well and that the structure is simple, compact and light in weight. My improved construction is such that a high speed engine has its valve mechanism operated by comparatively slow speed operating means for it is observed that the gear 82 rotates at relatively slow speed and this arrangement 90 serves to reduce friction and wear.

What I claim is:

1. An engine and combined oil pump and valve driving mechanism therefor, comprising a journal pin, a pump cylinder suspended on said journal pin and adapted to oscillate, a piston in the cylinder, a connecting rod secured to the piston, an eccentric driven by the engine, an eccentric strap made on the connecting rod and confined on the eccentric, and a gear made on the connecting rod eccentric strap and being concentric with the aforesaid eccentric to operate the engine valve gear. 95

2. A combination oil pump and valve driving mechanism for engines comprising an engine cylinder and crank shaft assembly, a valve for governing the intake and discharge of gas to and from the cylinder, an oil pump cylinder supported in such a manner as to oscillate, an eccentric on the engine crank shaft, a piston and crank connecting rod working in the oil pump cylinder and operated by the eccentric, a drive gear made on the crank connecting rod and adapted to be moved in an orbital path by the eccentric, and a gear meshing with and rotated by the drive gear and adapted to rotate the aforesaid valve. 105

3. An engine comprising a crank case, a cylinder and crank shaft assembly, a rotatable valve in the cylinder, a gear mounted on the cylinder head to rotate the valve, a valve shaft disposed alongside the cylinder, 115 a pinion on the upper end of the shaft meshing with the valve drive gear, a gear attached to the inner end of the shaft, a driven gear journalled on the crank case and meshing with the last named gear, said last 120 gear 125 journalled on the crank case and meshing with the valve drive gear, a gear attached to the inner end of the shaft, a driven gear journalled on the crank case and meshing with the last named gear, said last 130

named gear having internal gear teeth, an oil pump, and means adapted to drive the pump from the internal gear teeth.

4. A valve or pump drive mechanism for gas engines comprising in combination, a crank shaft, an eccentric fixed thereon, a rotating gear by which the valves of the engine are operated, a non-rotating gear journaled on the eccentric and meshing with the first gear, and blank tooth spaces made on one of the gears adapting one of the gears to slip across the teeth of the other gear when the eccentric is in its upper and lower position.
5. An engine comprising in combination, a crank case, a cylinder and crank shaft assembly, a valve seat in the cylinder, a rotatable valve in the cylinder working against the seat, a gear mounted on the cylinder head to rotate the valve, a valve shaft disposed alongside the cylinder, a pinion on the outer end of the shaft meshing with the valve drive gear, a gear fixed on the inner end of

the shaft, a driven gear journaled on the crank case and meshing with the last named gear to drive the valve shaft, an oil force feed pump, and drive means operating the pump and therefrom the aforesaid gear journaled on the crank case.

6. An engine comprising a crank case, a cylinder and crank shaft assembly, an oil pump cylinder, a piston in the cylinder, a connecting rod anchored to the piston, an eccentric strap carried on the connecting rod, gear teeth made on the external portion of the eccentric strap thereby providing a non-rotatable gear, a gear journaled on crank case, means operating between the eccentric strap and last named gear to drive said last named gear, and a valve in the cylinder adapted to be driven from last named gear.

In testimony whereof I affix my signature.

JOHN NEWMANN.
